(**) Term: **14 Years**

(57) **CLAIM**

The ornamental design for a golf headstrap for plumb bob alignment, as shown and described.

(21) Appl. No.: **29/408,745**

DESCRIPTION

(22) Filed: **Dec. 15, 2011**

FIG. 1 is a perspective view of a golf headstrap for plumb bob alignment embodying our design;

(51) LOC (9) Cl. **21-02**

FIG. 2 is a front view of the golf headstrap for plumb bob alignment;

(52) U.S. Cl. **D21/791**

FIG. 3 is a rear view of the golf headstrap for plumb bob alignment;

(58) Field of Classification Search D21/789,

FIG. 4 is a right side view of the golf headstrap for plumb bob alignment;

D21/791; 473/208, 210, 274

FIG. 5 is a left side view of the golf headstrap for plumb bob alignment;

See application file for complete search history.

FIG. 6 is a top view of the golf headstrap for plumb bob alignment; and,

(56) **References Cited**

FIG. 7 is a bottom view of the golf headstrap for plumb bob alignment.
